WRITING INSTRUMENT

Charles M. Tursky, Englewood, N. J.

Application November 28, 1947, Serial No. 788,336

11 Claims. (Cl. 120—42.03)

1

The present invention relates to writing implements and similar instruments in which a retractable working point projects from the end of an elongated body.

An object of the present invention is to provide, in an instrument of this kind, simple means for instantaneously displacing the working point from retracted into extended position and vice versa.

Another object of the invention is to provide an instrument of the character described in which extension and retraction of the working point may be effected by simple manipulation of one and the same button.

A further object of the invention is to provide an instrument of this character in which the working point may be extended by finger pressure and retracted by a sudden release of pressure, being automatically held in its extended position when the release of the finger pressure is gradual.

A more specific object of the invention is to provide a ball point pen provided with a spring-pressed button at the end opposite the ball point, depression of this button against the action of the spring being effective to lock the ball point in extended position from which it may be quickly retracted by a flip of the finger.

In ball point pens, where a danger of leakage ordinarily does not exist, it is sometimes found economical or expedient to dispense with the separable cover usually provided in fountain pens, and to make the ball point retractable in order to protect the lining of the user's pocket from direct contact with the ink-carrying ball. In most instances, however, the operation of the retracting mechanism provided for that purpose is so involved that the hurried user is likely to pocket his pen without the precaution of retracting it, the complexity of the mechanism thus defeating its purpose. The invention aims at avoiding these shortcomings by the provision of a quick-working, efficient and easily manipulable retracting mechanism.

The above and other features will become apparent from the following detailed description of a now preferred embodiment of the invention, taken in conjunction with the accompanying drawing in which:

Fig. 1 is a sectional elevation of a ball point pen according to the invention, shown in the extended position of the ball point;

Fig. 2 is a view similar to Fig. 1, with the ball point in retracted position;

Fig. 3 is a fragmentary sectional elevation,

2

showing the pen mechanism in the process of being manipulated;

Fig. 4 is an elevational view of an element of the pen assembly; and

Fig. 5 is a cross section taken on line 5—5 of Fig. 2.

Surrounded by the barrel 10 of the pen, Figs. 1 and 2, are a cartridge 11, a coil spring 12, an adapter 13, a thrust washer 14, a lock washer 15, and an operating member or button 16 surrounded by a sleeve 17. A gland 18 threadedly engages the upper end of the barrel 10 and cooperates with a shoulder 19 on the member 16, thereby limiting the upward movement of the latter.

The cartridge 11 may be of conventional form, comprising an ink-holding tube 20 and a ball point 21 which, in the extended position shown in Fig. 1, projects beyond the lower end of barrel 10. The expanding coil spring 12 bears upon a shoulder 22 of barrel 10 and also upon the lower face of the head 23 of adapter 13 which straddles and securely engages the upper end of cartridge tube 20. Thrust washer 14 has a beveled profile and concentrically surrounds the stem 24 of adapter 13 which is frictionally slidable therein. Also surrounding the stem 24 is the stop washer 15 whose aperture 25, however, is sufficiently large to permit this washer to assume either a position perpendicular to the stem 24, as shown in Figs. 2 and 3, or an inclined position, as shown in Fig. 1. The end of stem 24 slidably fits into the bore 26 of actuating member 16, said bore being sufficiently deep to permit the member 16 to engage washer 15 before coming into engagement with stem 24.

The operation of the retracting mechanism according to the invention is as follows:

The sleeve 17, shown in elevation in Fig. 4, is beveled at the underside so that the edge 27 extends below the edge 28 thereof. In the position illustrated in Fig. 1, one side of the lock washer 15 abuts the edge 27 of sleeve 17 while the other edge, 28, is sufficiently recessed to permit the washer 15 to assume the inclined position shown,

in which position the washer frictionally engages the stem 24 and thereby prevents the coil spring 12 from raising the adapter 13; hence the ball point 21 will remain extended as illustrated. Although the actuating member 16 is free to slide up and down in the sleeve 17, the ball point 21 will be locked in place by the washer 15 and will not yield, even under substantial pressure exerted by the writer. To retract the point, the opera-

tor pushes down the button 16 until it bears upon

the lock washer 15, the latter in turn abutting the conical face of washer 14 whose other face comes to rest against a shoulder 29 of barrel 10, as seen in Fig. 3. The annular underface 30 of member 16 places the lock washer 15 in a position transverse to the stem 24 which, in this position of washer 15, is free from engagement with the latter.

It will be seen that, were the washer 15 to remain in its horizontal or transverse position after the button 16 has been released, the spring 12 would be free to displace the adapter 13 and, with it, the cartridge 11 in an upward direction, thereby withdrawing the point 21 into the barrel 10 as shown in Fig. 2. To accomplish this result, it will merely be necessary to release the pressure upon actuating member 16 with such suddenness that the spring 12 will expand almost instantaneously, without giving the thrust washer 14 time to overcome its own inertia and follow the upward movement of the stem 24. Stated mathematically, the force f which tends to entrain the thrust washer 14 will be a function of the coefficient of friction between this washer and the stem 24, while the reaction force opposing a movement of washer 14 may be expressed as the product of the mass m of the washer and the acceleration a . Hence, if the spring 12 be permitted to impart to the stem 24 such an acceleration that the product $m \cdot a$ is greater than the force f , the thrust washer 14 will not leave its place until the shoulder 31 of adapter 13 strikes its underside. Once the washer 14 has been set in action, it will act to tilt the lock washer 15 whereupon the further movement of stem 24 will be prevented in the manner previously set forth.

If, however, it is desired to lock the ball point 21 in the extended position shown in Fig. 1, the operator again presses the button 16 as illustrated in Fig. 3, yet releases it slowly to enable the thrust washer 14 to follow the movement of stem 24. Thus the movement of the adapter-and-cartridge assembly will be arrested as soon as the lock washer 15 has pivoted about the edge 27 of sleeve 17, allowing the ball point 21 to rise for a distance only which is insufficient to retract it into the barrel 10.

It may be mentioned that if, after prolonged use, the bore of thrust washer 14 should become worn (as indicated in dotted lines in Fig. 3) to such an extent that the washer 14 will no longer be frictionally entrained by the stem 24, it will still be possible to manipulate the mechanism for the purposes of extending, locking and retracting the point 21, by simply turning the pen upside down when it is desired to lock the point in extended position. If the button 16 is now pressed and slowly released, the two washers 14 and 15 will follow the downward movement of the button, due to gravity, and will automatically assume the locking position shown in Fig. 1. For retracting, the same procedure will be followed in the normal position of the pen and, if the bore of washer 14 has been widened sufficiently, a sudden release or flipping of the button 16 will not be necessary.

Although the invention has been described with particular reference to ball point pens, it is to be understood that the invention is not limited to such pens or to writing implements in general, but that it may be used in connection with punching or cutting devices and other instruments of similar character. Furthermore, the invention may be embodied in various other forms representing modifications and adaptations of the arrange-

ment described and illustrated, without exceeding its spirit and departing from its scope as defined in the objects and in the appended claims.

I claim:

1. In an instrument having a retractable working point, in combination, an elongated member having one end secured to said working point, a locking member surrounding said elongated member and having an aperture wider than the cross section of said elongated member whereby to assume a first position spaced from said elongated member and a second position of frictional engagement with said elongated member, actuating means slidably surrounding said elongated member and being adapted to place said locking member in said first position while displacing said elongated member in one sense, spring means tending to displace said elongated member in the opposite sense, and a thrust member for frictional engagement with said elongated member to displace said locking member from said first into said second position upon being entrained by the movement of said elongated member in said opposite sense.

2. The combination according to claim 1 wherein said thrust member surrounds said elongated member and is provided with an inclined surface facing said washer.

3. The combination according to claim 1, further comprising shoulder means on said elongated member, said shoulder means being adapted positively to entrain said thrust member after said elongated member has moved a predetermined distance in said opposite sense.

4. In an instrument having a retractable working point, in combination, an elongated member having one end secured to said working point, a locking washer surrounding a portion of said elongated member adjacent the other end thereof, said washer having an aperture wider than the cross section of said portion whereby said washer will frictionally engage said portion in a position inclined with respect thereto but will surround said portion with clearance in a position perpendicular thereto, an actuating member slidably surrounding said other end and adapted to exert an axial thrust upon said elongated member, spring means tending to displace said elongated member axially against the action of said actuating member, the latter being adapted, when actuated, to displace said washer from said inclined perpendicular position whereby said elongated member will be freed for axial movement, a thrust member surrounding said portion in limited frictional engagement therewith, abutment means limiting the entrainment of said thrust member by said elongated member when the latter is displaced by said actuating member, and abutment means cooperating with said thrust member to tilt said washer into said inclined position when said thrust member is entrained by said elongated member moving under the action of said spring means.

5. The combination according to claim 4 wherein said thrust member is provided with a beveled profile facing said washer.

6. The combination according to claim 4 wherein the surface of said actuating member facing said washer is perpendicular to said portion.

7. The combination according to claim 4, wherein said portion terminates in a shoulder adapted positively to entrain said thrust member after said elongated member has moved a prede-

terminated distance under the action of said spring means.

8. An instrument comprising a tubular member, an elongated member slidably held in said tubular member, a working point secured to one end of said elongated member and adapted retractably to project from said tubular member, spring means tending to displace said elongated member so as to retract said working point into said tubular member, an actuating member slidably engaging the other end of said elongated member and adapted to displace the latter against the action of said spring means, a locking washer surrounding a portion of said elongated member adjacent said actuating member, said washer having an aperture wider than the cross section of said portion whereby said washer will frictionally engage said portion in a position inclined with respect thereto but will surround said portion with clearance in a position perpendicular thereto, a thrust washer disposed adjacent said locking washer at the side thereof opposite from said actuating member, said thrust washer surrounding said portion in limited frictional engagement therewith, a shoulder on said tubular member for limiting the movement of said thrust washer in the direction of said working point, said actuating member being adapted to cooperate with said thrust washer so as to bring said locking washer into said perpendicular position whereby said elongated member will be freed for axial movement, abutment means cooperating with said thrust washer to tilt said locking washer into said inclined position when said thrust wash-

er is entrained by said elongated member moving under the action of said spring means, whereby further movement of said elongated member will be prevented prior to retraction of said working point into said tubular member, and a shoulder on said elongated member adapted positively to entrain said thrust washer after said elongated member has moved a sufficient distance, under the action of said spring means, to retract said working point into said tubular member.

9. An instrument according to claim 8, wherein said abutment means comprises an edge of a beveled sleeve surrounding said actuating member.

10. An instrument according to claim 9, further comprising guiding means for said actuating member, said guiding means being adapted to retain said actuating member and said sleeve within said tubular member.

11. An instrument according to claim 8, wherein the surface of said thrust washer facing said locking washer is conical.
